H. KOEPLINGER.
DEVICE FOR PERFORATING FIGURED IRON.
APPLICATION FILED FEB. 26, 1912.

Patented Aug. 4, 1914.

UNITED STATES PATENT OFFICE.

HERMANN KOEPLINGER, OF VIENNA, AUSTRIA-HUNGARY.

DEVICE FOR PERFORATING FIGURED IRON.

1,105,800.

Specification of Letters Patent. Patented Aug. 4, 1914.

Application filed February 26, 1912. Serial No. 679,925.

To all whom it may concern:

Be it known that I, HERMANN KOEPLINGER, a subject of the Emperor of Austria-Hungary, residing at 23 Herklotzgasse, Vienna, XV, in the Empire of Austria-Hungary, have invented new and useful Improvements in Devices for Perforating Figured Iron, of which the following is a specification.

10 The present invention is a further development of the device for perforating figured iron described in my U. S. Letters Patent No. 989159.

15 The invention by means of a peculiar formation of the punch and the swage enables perforations bounded at one end by a bent flange, and at the other end by a bent web bridge to be made in one operation. This particular kind of perforation, which is 20 known *per se*, has hitherto been produced by the use of several tools as can be seen for example from the specification of German Patent No. 184013.

25 The present invention relates to means for perforating figured window irons having a curved flange opening and a curved web bridge opening. This form of iron is well-known in the art, and the usual manner of producing or forming the same prior to my 30 invention was to form the perforations in the web material by the gradual operation of a plurality of tools. In the course of this operation the web was bent up and down across suitable cross bar bearings, resulting in a very substantial weakening of the material of the web. Moreover, after using 35 perforating mechanisms such as heretofore employed, fairly extensive finishing of the transverse openings or slots was required, 40 because despite the greatest care which could be exercised it was not possible to obtain a clean cut perforation in one single operation.

45 The object of my invention is to obviate the disadvantages inhering in existing methods, and I accomplish this object by forming the opening in the iron by a single tool, consisting of an edged or flanged central portion, provided at both sides with curved jaws having knife-like cutters for the production of the flange openings and web bridge openings.

50 Now I have found by exhaustive experiments that it is possible by means of a further development of the devices described in my U. S. Letters Patent No. 989159 to

produce by means of a single tool and in a single operation the particular kind of perforation in question. This result is made possible by a peculiar formation of the punch in conjunction with a peculiarly constructed swage.

55 In the drawing Figure 1 shows the form of the opening or perforation known *per se*, in a longitudinal bar. Fig. 2 shows in perspective view the new tool for the production of the opening. Fig. 3 shows a modification. Fig. 4 shows the improved swage comprising a new part for receiving the web portion of the figured iron and the known dove-tail guide for the swage portion receiving the flange of the iron. Fig. 5 shows in perspective view the part of the swage for receiving the flange of the iron. Fig. 6 shows a plan of the finished perforated iron bar.

60 The improved tool consists of a prismatic body 1, upon the front face of which are provided the cutting and bending jaws 2 for the production of the opening 2' obtained by the bending of the flange. Upon 65 the back of the middle portion of the tool are provided peculiarly shaped cutting and bending jaws 3 for producing the web opening 3' bounded by the web bridge. The jaw 3 rises, in the construction shown, from a 70 slightly higher point on the central portion of the tool than the flange bending jaws 2 and is provided on its edges with cutters 4 and 5 having as small a cutting angle as 75 possible.

80 The part 9 of the swage for receiving the flange α of the blank is identical with the part 9^a of the swage shown in the U. S. Letters Patent No. 989159. As is described 85 in the said Letters Patent there is provided in this part of the swage a plate 18 which supports the flange α and yields gradually in proportion as the tool is forced down.

86 To prevent the web γ of the channel iron being bent down during the punching of the 100 middle slot in the web and the bending of the web bridge there is provided according to the present invention in that half of the swage 20 which receives the web of the blank a movable block 21 which by its face 22 supports the web bridge while it is bent out. This supporting block is pressed by a strong spring 24 against the tool and yields in proportion as the bending of the web bridge 105 proceeds.

The depth t of the slot receiving the work corresponds to the height h of the web of the blank plus the height h' of the web bridge. The breadth b of the slot for the introduction of the tool corresponds to the thickness of the web of the channel iron. The depth w of the opening d through which the tool is passed corresponds with the depth w' of the middle portion 1 of the tool.

When the tool is pressed down through the opening o in the swage against the blank held therein, the rectangle 8 (see Fig. 1) is first punched out of the web. On the further descent of the tool the flange of the channel iron is separated from the web and bent out in the well known way and the contour of the opening formed by the bent out flange thus gradually developed. At this time the cutters 4 and 5 of the web bridge bender come into action and cut out in the web of the channel iron the lateral slits required for the bending out of the web bridges. On the further descent of the tool the flange opening is further bent out to the normal size and at the same time the web bridge is bent out by the jaw 3. As all the perforating, cutting and bending deformations take place while the material operated upon is inclosed on all sides, the contour of the opening produced by the new device must always correspond in all details with perfect accuracy with the final contour of the punching tool used. By this means all subsequent treatment of the contour of the hole is rendered superfluous notwithstanding the considerably simplified method of production. It is advisable to make the web bridge bender 3 (see Fig. 3) together with its cutters interchangeable as, apart from the easier method of production of the tool, the punch can in this case be employed as a universal tool for punching out various kinds of web profiles.

I claim:—

1. In means for making perforations in figured iron bounded by a bent out flange portion and a bent out web-bridge, a punch which consists of a bender provided with cutters corresponding to the perforation in the bent out flange portion of the work piece, a prismatic middle portion corresponding to the central perforation of the web of the work piece and a second bender provided with knife like cutters corresponding to the perforation in the bent out web bridge portion of the work piece.

2. In means for making perforations in figured iron bounded by a bent out flange portion and a bent out web bridge, a punch which consists of a bender provided with cutters corresponding to the perforation in the bent out flange portion of the work piece, a prismatic middle portion corresponding to the central perforation of the web of the work piece and a second bender corresponding to the perforation in the bent out web bridge, said bridge-bender being attached interchangeably to said flange bender.

3. In means for making perforations in figured iron bounded by a bent out flange portion and a bent out web bridge, the combination with a swage for holding the figured iron of a tool guided rectilinearly by the swage in the direction of the figured iron, said swage having means for supporting the web of the figured iron and elastic pressure means by which said supporting means are held against the penetrating tool during its descent.

In testimony whereof I have signed my name to this specification in the presence of two subscribing witnesses.

HERMANN KOEPLINGER.
